UNITED STATES PATENT OFFICE.

WILLIAM J. WILGUS, OF NEW YORK, N. Y., AND HOWARD A. CARSON,
OF MALDEN, MASSACHUSETTS.

METHOD OF CONSTRUCTING SUBAQUEOUS TUNNELS.

No. 829,190.

Specification of Letters Patent.

Patented Aug. 21, 1906.

Application filed February 10, 1906. Serial No. 300,494.

To all whom it may concern:

Be it known that we, WILLIAM J. WILGUS, of the city, county, and State of New York, and HOWARD A. CARSON, of the city of Malden, county of Middlesex, and Commonwealth of Massachusetts, citizens of the United States, have invented new and useful Improvements in Methods of Constructing Subaqueous Tunnels, of which the following is a full, clear, and exact description.

During the past thirty-five years there have been schemes proposed for constructing subaqueous tunnels by placing at the bottom of the water both inner and outer molds and depositing between the same and entirely around the inner one cement concrete, which when set or hardened is to constitute the tunnel-walls desired. This proposed method we deem impracticable, for, as we have learned by experience, concrete deposited under and in contact with water usually results in a far poorer product than when made and allowed to set in air. It usually also has numerous voids and cannot prudently be relied upon to prevent too-rapid percolation of water through it. There have also been proposed various schemes for sinking tubes of metal or other material, which when joined together at the bottom of the water unite to form a subaqueous tunnel; but processes hitherto proposed of connecting such tubes with sufficient accuracy and water-tightness as to be suitable for passenger-tunnels are difficult and uncertain.

The object of our invention is to furnish a process of laying subaqueous tunnels by which the objections above referred to and others will be obviated.

The process, broadly stated, is as follows: Having located an outer shell, which may be only imperfectly water-tight, upon a suitable foundation along the water-bottom, the water is expelled by pumping or air-pressure, or both, from the whole or a suitable portion of said shell, water being prevented by the use of compressed air, if necessary, from reentering the same. Concrete or other suitable material is then carried within said outer shell and formed into walls which are to compose the tunnel proper. If the water is at first excluded from only a portion of the outer shell, successive parts will be cleared of

water from time to time, and the true walls of the tunnel built in such portions until the whole is completed.

Referring to the drawings forming part of this specification, Figure 1 is a side sectional elevation of a subaqueous tunnel made in accordance with our process. Fig. 2 is a cross-section of the same on the line X X in Fig. 1. Fig. 3 is a cross-section on the line Y Y in Fig. 1. Fig. 4 is a cross-section on the line Z Z in Fig. 1. Fig. 5 is a longitudinal section of a subaqueous tunnel made in a slightly different manner. Fig. 6 is a cross-section of the outer shell, showing means for its adjustment when being located in position. None of these figures are drawn strictly to scale, but instead are diagrammatic in character.

In the drawings, 10 designates the bottom of the water in which the tunnel is to be laid. 11 is a channel or trench dredged out for the tunnel's reception; and 1 is the outer shell.

The first step in the process is the preparation of a suitable bed in the bottom of the water where the tunnel is to be built. This may in some cases require filling, in others, dredging. The latter case is assumed for illustration and description; but in either case the bed should approximate as closely as practicable to the required subgrade profile. Supports for the shells or molds 1 are then to be accurately placed and made secure to the bed. These "supports" or "saddles," as they are termed, may be made of timber, metal, or other suitable material, may be laid on a suitable bed and adjusted to proper position by wedges, as shown in Fig. 6, where 20 designates the wedges for the adjustments in profile and 21 in plan; or they may be bents of piles with timber or concrete upper surfaces, the same being so made and placed that the shells or molds when supported thereon will be tolerably true to line and grade. The next step in the operation is to sink through the water the outer shell, mold, or form 1, of metal, wood, or other suitable material, supporting and securing the same upon the saddles 2 a short distance from the bottom of the prepared bed 11. If this shell is laid in sections, such sections must be properly united together, the method of such union being described hereinafter. Concrete or

other suitable material is then introduced between the under surface of said shell and the bed beneath to form a foundation 3 for the tunnel-walls, as shown in Fig. 3. In 5 most cases the outer shell will be entirely surrounded by filling 6, of concrete, riprap, gravel, clay, or other material, depending upon the expense that can be afforded, the strength and weight of the shell, and other 10 circumstances.

In general, depending on the length of the subaqueous tunnel to be formed, the shell or mold will be lowered through the water in 15 sections of convenient length for handling, usually from fifty to five hundred feet. These sections are after being laid in the saddles 2, as already described, to be securely joined together end to end and the joints between them made as water-tight as is reasonably practicable. If compressed air is to be 20 used later to prevent the entrance of water, the joints may be made in a simpler and less water-tight way than would otherwise be permissible. For instance, the joints may be 25 wrapped, by the aid of divers, with stout canvas lapping onto two contiguous ends of shells and tightly held by wires or tourniquets, as at 7 in Fig. 1. This canvas will be covered by the outer filling of concrete or 30 other material 6, previously referred to, or by a limited covering 7' of grout or concrete.

In some cases we prefer to make the joints between contiguous sections in the manner shown in Fig. 5. Here the sectional shells 1 have bulkheads 8' at each end, and the contiguous sections are placed in the water a 5 short distance apart. The spaces between the contiguous bulkheads 8' and the spaces around the outer ends of the sections are 10 filled with grout 8" or a specially-prepared rich concrete which will be substantially water-tight when set or crystallized. Said bulkheads 8' should be made tight enough to prevent the leakage of cement grout through 15 them, and they should also be strong enough to withstand the head of grout and 20 preferably strong enough to resist the full head of water. Two contiguous bulkheads 8', with the special concrete 8" between 25 them, can be so dimensioned as to form together a bulkhead of any required strength. If such composite bulkheads 8' 8" are not 30 employed, we prefer to have bulkheads 8, placed in the outer shell at convenient 35 distances apart, and these will ordinarily be built into the shells before they are lowered. Each bulkhead constitutes a diaphragm entirely across the shell-sections and may be of 40 any suitable material—as, for example, wood 45 or metal. They are to be as nearly water-tight as is readily practicable, and they are to 50 be strong enough and thoroughly enough attached to the mold or outer shell to act as a 55 dam with a head of water due to their depth 60 below the upper surface of the surrounding

water when the shell is in its final position. In making these bulkheads 8 due attention is to be given to the fact that they are temporary. The bulkheads will divide the shell-sections into a series of cells or chambers, one 70 or more bulkheads to each section. For convenience in description these chambers will be referred to as "chamber A," "chamber B," "chamber C," &c., in the order in which subsequent operations of pumping and building 75 the tunnel-walls proper are to be carried on. Two pipes 9, with stop-cocks or plugs in each, should preferably be built into and through each bulkhead 8, one pipe near the top and the other near the bottom, to be used as later 80 described.

When a convenient length of the outer shell-sections constituting several chambers has been completed and the outer shell, if it 85 has been constructed of concrete, as we sometimes prefer to have it, has become sufficiently strong, the water may be pumped from the most convenient chamber, called "chamber A," usually at or near the shore, and further leakage into said chamber may be 90 prevented by the use of compressed air.

The work of constructing the tunnel proper may now be begun, the first step of which may be lining the interior surface of the outer shell with some waterproof material—such as 95 fine cement, pitch, or asphalt—in order to insure the waterproof character of the tunnel when completed. This lining is designated by the reference-numeral 4 in Figs. 3 and 4. The shell may, however, be so tight that no 100 further waterproofing will be necessary. The next step is to form the tunnel-walls proper, 5, in contact with said lining, employing any suitable supporting means for the concrete or other suitable material composing the ceiling 105 or roof of the tunnel and any suitable core-mold for the entire inner surface of the concrete, such supporting means or core-mold being too well known in the art to require 110 illustration in the drawings.

When the true tunnel-walls 5, including ceiling and invert, have been completed in chamber A, the water in the adjoining chamber B may be drawn through the intervening bulkhead 8 (shown in dotted lines in Fig. 1) 115 by means of the lower of said pipes 9 into the chamber A and from there ejected by suitable means, at the same time air being let into chamber B through the upper of the pipes 9. This air will be of normal pressure, if that 120 will suffice, but may be compressed, if necessary, to insure against leakage. When substantially all the water has been removed from the chambers A and B, the bulkhead between them may be removed and the waterproofing and the true tunnel-walls made in 125 chamber B in the same manner as in chamber A, the waterproofing, if used, and the true tunnel-walls being made continuous from one to the other of said chambers. In the same 130

manner the various other chambers and bulkheads are to be successively treated until the structure is completed.

While the operations in the chambers A and B are in progress, as above described, the various tasks of dredging, sinking outer shell-sections, and placing foundations under and material around the shell-sections may be in progress, so as to form additional chambers in the line of the tunnel.

The various steps in our process are shown more or less complete in Figs. 2, 3, and 4, where Fig. 2 illustrates the outer shell or mold 1 as supported upon the saddles 2 and with the water both within and without it. Fig. 3 shows the foundation 3 completed beneath the shell with the water removed and the waterproof lining 4 partially applied, and Fig. 4 shows the true tunnel-walls 5 completed and the protecting material 6 applied.

The foundation 3 may be composed not only of concrete, as described, but of broken stone, sand, or other suitable material in lieu thereof. While it is preferable also to construct said foundation after the outer shell has been placed in position in order that the contact between the same may be more intimate and perfect, the foundation may be laid first and the shell then located thereon, or the foundation may be partially formed and completed after the shell is placed thereon. Which particular arrangement is to be adopted depends much upon the character of the ground beneath. If too unstable or soft, piles may first be driven and the foundation laid thereon prior to the sinking of the shell-sections, while if the ground is firm the first-described method is more desirable.

Although we have described our process as applicable in the construction of concrete tunnel-walls, the process is equally valuable where brick or other material is to be used therefor.

We illustrate but a single line of tunnel; but it is evident that a double or other multiple line may be made by the same process, and sidewise communication between any two adjacent lines may be likewise made.

It is manifestly a difficult operation to build beneath the water a line of foundations exactly true as to grade and plan or even to locate a series of saddles 2 with precise accuracy. If the shell-sections are of substantial size, they may vary one with respect to its neighbors both in profile and in plan, as represented in Fig. 1. Inasmuch as the irregularly-contacting section-terminals can be made sufficiently water-tight by the processes herein set forth and the cement walls can be made to conform to the irregular inner surfaces of the shell-sections, while entirely true as to interior surface proper, all such imperfection of foundation or saddles is of no moment in our process of constructing subaqueous tunnels.

What we claim as our invention, and for which we desire Letters Patent, is as follows, to wit:

1. The herein-described method of constructing subaqueous tunnels, the same consisting in locating an outer shell or mold at the bottom of the water on a suitable foundation; making the same substantially watertight; removing the water therefrom, and finally forming the tunnel-walls proper within said shell or mold. 70

2. The herein-described method of constructing subaqueous tunnels, the same consisting in locating an outer shell or mold on a suitable foundation at the water-bottom, removing the water therefrom and preventing its return by the aid of compressed air, and then forming the tunnel-walls proper within said shell or mold. 80

3. The herein-described method of constructing subaqueous tunnels, the same consisting in locating an outer shell or mold on a suitable foundation at the water-bottom; removing the water therefrom and preventing its return by the aid of compressed air; then rendering the interior surface of said shell or mold waterproof, and finally forming the tunnel-walls proper within said shell in contact with said waterproof surface. 90

4. The herein-described method of constructing subaqueous tunnels, the same consisting in locating an outer shell or mold on a suitable foundation at the water-bottom; removing the water therefrom and preventing its return by the aid of compressed air; and finally forming of concrete the tunnel-walls proper within said shell. 95 100

5. The herein-described method of constructing subaqueous tunnels, the same consisting in locating an outer shell or mold on a suitable foundation at the water-bottom; making said shell or mold more or less watertight; removing the water therefrom and preventing its return by the aid of compressed air; coating the inner surface of said shell 110 with a waterproofing material; and, finally, forming the tunnel-walls proper of concrete in contact with said coating. 115

6. The herein-described method of constructing subaqueous tunnels, the same consisting in first locating an outer shell or mold on suitable supports at the water-bottom but allowing a space between said bottom and under surface of said shell or mold; filling said space with foundation material; removing the water from said shell or mold and preventing its return by the aid of compressed air; and then forming the tunnel-walls proper within said shell or mold. 120

7. The herein-described method of constructing subaqueous tunnels, the same consisting in locating a series of outer shell-sections on suitable foundations at the water-bottom; temporarily preventing the passage of water from one to another of said sections; 125 130

removing the water from successive sections and preventing its return by the aid of compressed air; and then forming the tunnel-walls proper in the successive sections.

8. The herein-described method of constructing subaqueous tunnels, the same consisting in first locating an outer shell or mold on suitable slightly-elevated supports at the water-bottom; constructing a foundation between said shell and water-bottom; removing the water from said shell; coating the interior of said shell with a waterproofing material, and then forming of concrete the tunnel-walls proper within said shell.

9. The herein-described method of constructing subaqueous tunnels, the same consisting in first locating a series of saddles along the water-bottom in the line of the proposed tunnel; placing a series of longitudinal sections of outer shells on said saddles; making the joints between adjacent ends of the sections substantially water-tight by wrapping flexible material thereabout, and covering with concrete or grout; surrounding the shells with foundation and filling material; removing the water from said outer shells and, finally, forming the tunnel-walls proper within said shells.

10. The herein-described method of constructing subaqueous tunnels; the same consisting in first locating a series of saddles along the water-bottom in the line of the proposed tunnel; placing a series of longitudinal sections of outer shells on said saddles; making the joints between adjacent ends of the sections substantially water-tight by wrapping flexible material thereabout; and covering with concrete or grout; surrounding the shells with foundation and filling material; removing the water from said outer shells and preventing its return by the aid of compressed air; and, finally forming the tunnel-walls proper within said shells.

In testimony that we claim the foregoing invention we have hereunto set our hands this 8th day of February, 1906, and the 6th day of February, 1906, respectively.
